(57) **CLAIM**

The ornamental design for a transfer switch enclosure, as shown and described.

DESCRIPTION

FIG. 1 is an isometric view of a transfer switch enclosure in accordance with the present invention;

FIG. 2 is a front elevational view of the transfer switch enclosure of FIG. 1;

FIG. 3 is a side elevational view of the transfer switch enclosure of FIG. 1;

FIG. 4 is a top plan view of the transfer switch enclosure of FIG. 1;

FIG. 5 is a bottom plan view of the transfer switch enclosure of FIG. 1;

FIG. 6 is a rear elevational view of the transfer switch enclosure of FIG. 1;

FIG. 7 is an isometric view of an alternate embodiment of a transfer switch enclosure in accordance with the present invention;

FIG. 8 is a front elevational view of the transfer switch enclosure of FIG. 7;

FIG. 9 is a side elevational view of the transfer switch enclosure of FIG. 7;

FIG. 10 is a top plan view of the transfer switch enclosure of FIG. 7;

FIG. 11 is a bottom plan view of the transfer switch enclosure of FIG. 7; and,

FIG. 12 is a rear elevational view of the transfer switch enclosure of FIG. 7.

Broken lines shown in the drawings illustrate portions of the transfer switch enclosure, and form no part of the claimed design.
